UNITED STATES PATENT OFFICE.

GUSTAV ADOLF SACHS, OF EUGENE, OREGON.

EXTENSION-STOCK FOR PISTOLS.

1,266,633.

Specification of Letters Patent. Patented May 21, 1918.

Application filed September 25, 1917. Serial No. 193,178.

To all whom it may concern:

Be it known that I, GUSTAV ADOLF SACHS, a citizen of the German Empire, and a resident of Eugene, in the county of Lane and State of Oregon, have invented certain new and useful Improvements in Extension-Stocks for Pistols, of which the following is a specification.

The object of my invention is to provide a simplified arrangement for connecting a pistol with an extension stock, thereby enabling the marksman to use a pistol very much after the fashion of a rifle, and thus obtain greater accuracy in shooting. Another advantage of this construction resides in the fact that the extension stock is detachable from the pistol, and the two parts can therefore be packed more readily than if their connection was permanent.

In the preferred form of my invention the extension stock is so constructed that it will at the same time form a holster in which the pistol may be carried when not in use. Various additional features which lend special advantage to the construction now devised by me will be fully described below in connection with the accompanying drawings and the novelty of the invention will then be pointed out in the appended claims.

A typical example of my invention is illustrated in the accompanying drawings in which—

Figure 1 is a side elevation showing a pistol in connection with my improved holster and extension stock;

Fig. 2 is a perspective view showing how the improved holster may be suspended from a belt;

Fig. 3 is a top view of the improved holster;

Fig. 4 is a side elevation of the holster with parts in section;

Fig. 5 is a vertical section on the line 5—5 of Fig. 4;

Fig. 6 is a detail side elevation showing the front portion of the holster on an enlarged scale;

Fig. 7 is a partial vertical section on the line 7—7 of Fig. 6; and

Fig. 8 is a detail end view of one of the parts of the pistol clamp or holder.

The holster 10 is made of substantially the usual shape, being considerably wider at one end than at the other so as to properly receive the pistol 11 with the handle 11', (see Fig. 4). At its wide end the holster is open

for the insertion and removal of the pistol and has a flap 10' which may be held in the closed position by means of a pin and slot connection such as indicated at 12. On the outside and adjacent to the wider end, the holster is provided with a spring clip 13 substantially U-shaped as shown best in Figs. 2 and 3, said clip ranging lengthwise of the holster and having its opening toward the narrow end thereof. This clip is generally made of brass and enables the holster with the pistol therein to be readily suspended from a belt or other part of the clothing as indicated at 14 in Fig. 2.

The holster is stiffened longitudinally both at the upper and at the lower edge. At the lower edge a rib 15 of fiber or other suitable material is provided, the rear end of which is practically at the joint or hinge connecting the flap 10' with the body 10 of the holster. At its forward end this fiber rib is continued upwardly to the upper edge of the holster as indicated at 15', and is formed exteriorly with a concaved seat 15'' for the handle 11' of the pistol. The leather covering or like material used for the holster is preferably riveted to said lower stiffener or rib 15 as shown in Figs. 1, 2, 4. Along the upper edge of the holster there is another stiffener in the nature of a strip 16 of steel or like material preferably incased in leather or the like as indicated in Figs. 4, 5 and 7, and having its exposed rear end bent downward and forward as indicated at 16', so that this rear end will form a broader bearing for the upper end of a transverse elastic butt member 17, which is located and secured at the junction of the holster body 10 with the flap 10', and is also preferably incased in leather, said butt member being thus held permanently at the joint or hinge. The lower end of this elastic butt member is adapted for supported engagement with the rear end of the lower stiffener 15.

At the front of the holster I provide means for connecting it firmly yet detachably with the handle 11' of the pistol. In the particular construction shown this means comprises two plates 18 of fiber or like material provided at their lower ends with lugs 18' which register with a forwardly extending ridge or stop 15'' (see Fig. 4), which serves to engage the end of the pistol handle (see Fig. 1). Through these plates 18 and through the forward portion 15'' of the stiffener, as well as

through the body 10 of the holster extends a transverse pivot pin 19 on the ends of which are secured two disks 20 and 20' respectively. One of these disks 20 may be 5 integral with the pivot pin; the other is shown as secured thereto detachably by means of a screw 21, said disk 20' having a square hole to fit over a square portion 19' of the pivot pin, and being also recessed 10 on its outer surface so that the head of the screw 21 may be counter-sunk. Each of the disks 20 and 20' is provided with an eccentric aperture which is indicated at 20'' (see Fig. 8) for receiving a screw 22, by 15 means of which a pivotal connection is established between the said disks and a holder strap or loop 23 preferably covered with leather or the like on its major portion. This loop or strap which is substantially U-shaped embraces the forward end 20 of the holster and is adapted to fit around the pistol handle 11', as shown in Fig. 1. The pivot 19 and the parts connected therewith may be turned by means of a handle 25 20^a, preferably formed integral with the disk 20. A stop such as 24 may be provided to limit the movement of said lever when it reaches its service position (see Fig. 1).

30 When it is desired to insert the pistol in the holder 23 and firmly connect the pistol with the holster the lever 20^a is first swung to the position indicated by full lines in Fig. 6 to bring the eccentric pivotal connection 22 forward of the axis of the pivot 19, so that ample space is provided for inserting the pistol handle 11', which is made to rest on the stops 15^a and 18', the transverse curved seat 15'' assisting in 35 properly positioning the pistol. The handle 20^a is then swung rearwardly as indicated by the arrow to the position shown in dotted lines in Fig. 6 and in full lines in Fig. 1, thereby drawing the loop or holder 40 23 longitudinally toward the holster and clamping the pistol handle firmly in position. The parts are now in the condition illustrated by Fig. 1, and the holster may be used as an extension stock. The elastic 45 butt member 17 which practically engages the marksman's shoulder finds a supported engagement at both ends, on the widened rear end 16' of the upper stiffener 16 and on the rear end of the lower stiffener 15 respectively; thus while the holster is braced 50 longitudinally to a sufficient extent to make it a practically rigid stock, sufficient elasticity is provided by the transverse member 17 to take up the jars and make shooting 55 with the weapon more comfortable.

60 The hole 23' indicated in Fig. 6 is simply an extra hole in the strap or loop 23 to enable its effective length to be increased

when desired, it being understood that in 65 this case the screw 22 on that side would be removed and the strap then adjusted so as to bring the hole 23' into registry with the hole 20', whereupon the screw 22 would be inserted again. This extra adjustment 70 might be provided at each end of the strap 23.

I claim:

1. A longitudinally-stiffened pistol holster provided with a flap at one end and with a transverse elastic butt member secured permanently along the joint of said flap with the body of the holster, and means for securing a pistol to the other end of the holster exteriorly whereby the holster may be used as an extension stock. 75
2. A pistol holster provided with an opening at one end, a flap for covering said opening, a transverse butt member at the joint of the flap with the body of the holster, a longitudinal stiffening member provided with a return bend adjacent to one end of said transverse member, and means for securing a pistol to the other end of the holster exteriorly. 85
3. A pistol holster provided with a flap and with stiffeners extending along the top and bottom edges of the holster to said flap, an elastic butt member located at the junction of the flap with the holster body and having its ends in supported relation to 90 the rear ends of said stiffeners, and means for fastening a pistol to the front portion of the holster exteriorly. 95
4. An extension stock for pistols, provided with a seat for the pistol handle, a loop arranged adjacent to said seat, to embrace the pistol handle, a member journaled in said stock and having an eccentric pivotal connection with said loop, and a handle on said member. 100
5. An extension stock for pistols, provided with a seat for the pistol handle, an eccentric journaled in said stock adjacent to said seat, and a holder arranged to engage the pistol handle and operated by 105 said eccentric to tighten or loosen its hold on said handle. 110
6. An extension stock for pistols, provided with a seat for the pistol handle, a holder connected with said stock and adapted to engage the pistol handle, and means for drawing said holder lengthwise of the stock to clamp the pistol handle. 115

In testimony, that I claim the foregoing as my invention, I have signed my name in 120 presence of two subscribing witnesses.

GUSTAV ADOLF SACHS.
